TYPEWRITING MACHINE

Russell G. Thompson, West Hartford, Conn., assignor to Underwood Elliott Fisher Company, New York, N. Y., a corporation of Delaware

Application June 21, 1937, Serial No. 149,343

2 Claims. (CL 197—25)

This invention relates to typewriting machines and with regard to certain more specific features thereof to an improved type action and means for effecting and controlling the movement of the parts thereof. While the invention is shown and described in connection with a power-driven typewriter it will be obvious that several features of the invention are applicable to manually operated machines.

The invention has for one of its objects to provide a group of type actions each of which is suited to the particular requirements of a power-driven machine. It is well known that such machines present a particularly difficult problem because of the shocks incident to the engagement of the individual type actions with the driving means, and also because of the peculiar character of the blow on the engaged member by the driving means. In power-driven typewriters the mechanism for accomplishing the movement of the type bar to and from the platen is entirely removed from the control of the operator and the action of the power means when engaged is inclined to loosen and destroy the parts of the type action and increase the noise incident to all contacts.

Another difficulty presented by the employment of the power-drive unit and the shock incident to engagement therewith is the tendency of the type bar to vibrate as it approaches the platen in consequence of which the type bar is apt to impinge on the type bar guide adjacent the printing point and destroy the regularity of the writing and also result in exceptional wear of the parts.

The type action here involved is of the noiseless character and it is an object of the invention to so improve and modify such a type action as to make it capable of substantially silent power operation without the interposition of any elastic or yielding connections between the power-drive unit and the type bar, it being particularly an aim of the invention to adapt the thrust principle of operation of a type bar to a fluted roller or other form of constantly operating power-drive unit so that the labor of the operator is reduced to the mere selection of the proper keys and engagement thereby of the actuating device of the type bar with the power-drive.

It is a further aim of the invention to produce a quiet power-driven machine in which the thrust principle of type bar operation is used in connection with a standard four-bank keyboard and a single shift platen, and in which a number of type bars segmentally arranged for selective ad-

vance to the printing point are provided with upper and lower type heads each of which may have two type characters, the movement of each type bar in connection with such a construction being in variable paths controlled by different keys at 5 the keyboard.

Another object of the invention is to insure the continuance of a toggle locked position of the supporting means for the forward end of the type bar as it completes its movement to the 10 platen and to a reasonable extent away therefrom whether the type bar be moved in one path or the other by the selection of one or the other of the two keys which control its operation. Thus the pivotal axes of the bar are held firmly when the bar is in the vicinity of the type guide and vibratory tendencies are checked.

Other objects are to provide improved means for deadening the sounds originating in contacts of the various parts of the action. This includes 20 the contact of the type with the paper on the platen, the stopping of the power-drive lever in its advance of the type bar and the return of the energy storing device or hammer to its position of rest.

Another object of the invention is to provide a sturdy, inexpensive and generally improved power-drive unit between the selecting keys and the type bars, such unit being extremely compact and quiet in its operation and being especially adapted to the actuation of a series of type bars arcuately arranged above the unit, and correspondingly suited to a control of the carriage in its escapement, case shift, return and back spacing movements.

Other objects will be in part obvious and in part particularly pointed out as the description of one preferred embodiment of the invention proceeds.

In the drawings:

Fig. 1 is a view in top plan of a power-driven typewriting machine comprising the present invention.

Fig. 2 is a view in fore-and-aft section of the machine shown in Fig. 1.

Fig. 3 is a fore-and-aft sectional view through the machine showing the type action advanced from its normal position of rest, as shown in Fig. 2, to a position of lower-case printing by the upper head of the type bar.

Fig. 4 is a fore-and-aft sectional view through the machine showing a type action advanced from its normal position, as shown in Fig. 2, around the same pivotal centers, as shown in Fig. 3, but with the platen elevated to receive the im-

print of the upper case character of the upper head of the type bar.

Fig. 5 is a fore-and-aft section through the machine showing the same type action as seen in Figs. 2 to 4 inclusive but as viewed from the opposite side and with the type bar in its retracted position.

Fig. 6 is a fore-and-aft section through the frame showing the same type action as seen in Fig. 5 but as operated by the selection of another key at the keyboard to advance the type bar for printing by a lower-case character on the lower head of the bar.

Fig. 7 is a view in perspective of one of the type action hangers.

The machine is shown generally in Figs. 1 and 2 of the drawings. It comprises a frame having side walls 21 and 22 connected by a front bar 23 and by a rear bar 24. The side walls are further connected by a bar or backbone 25, cross bars 26 and 27 and a top plate 28.

The top plate has an arcuate bar 30 upon which are mounted the forward ends of a multiplicity of type actions indicated generally at 31. The type actions are radially arranged and have rear supports in an arcuate bar 32 fixed to the top plate and provided with comb slots 33 to guide type bars 34. The latter are further guided by comb slots 35 and 36 in arcuate webs 37 and 38 projecting downwardly from a guide member 40 suitably mounted on the top plate below a cover 41.

Toward the rear of the machine a center-tie 42 is adjustably fixed for slight fore-and-aft movement on a cross bar 43 and this center-tie carries the pivotal supports for a case-shifting rocker 44, arms 45 of which pivotally support a track 47 which through anti-friction bearings supports a carriage rail 48 connected to suitable carriage end frames in which a roller platen 50 is mounted. The carriage also includes a rail 51 which, in the transverse movements of the carriage, is biased against a forward face of an upstanding arm 52 of the center-tie. A backing screw 53 is threaded in the upper portion of the rear wall 24 and suitably resists printing pressures on the platen. This center-tie construction and the means for adjusting the center-tie relatively to the frame are described and claimed in my copending application filed Feb. 20, 1937, Serial No. 126,902.

A magazine 55 is secured to spaced webs 56 extending rearwardly from the center-tie and contains one or more tabulator stop blades 57 adapted for power operation, as clearly shown and described in my copending application filed April 1, 1937, Serial No. 134,324.

Any desired means may be employed for raising and lowering the carriage frame and consequently case-shifting the platen, but it is preferred to make use of a link 58 having its upper end connected to the rocker frame 44 and its lower end connected to a link 60 by a pivot stud 61. The link 60 in turn is pivotally connected at 62 with an arm 63 adjustably secured to the frame 65 of the machine. When the toggle involving links 58 and 60 is straightened the forward side of frame 44 is elevated depressing the pivotal connection 45 and lowering the platen to its normal or lower case position. This position is determined by an adjustable screw 64 mounted on the carriage coming in contact with a boss 65 on the center-tie. A pivot stud 66 connects one end of a link 67 with a lever arm 68, the other end of link 67 being connected at pivot 61 to both link 58 and link 60. Lever arm 68 is suitably connect-

ed to an actuator 70 which carries pawls adapted to be moved into engagement with a toothed drive shaft 71 by operation of a case-shifting key at the keyboard. Depression of this key causes a pawl to engage on the forward side of drive shaft 71 and be moved downwardly carrying the actuator 70, which breaks toggle 58-60, pulling link 58 downwardly and rocking frame 44 to elevate the carriage until the head of pivot stud 66 comes against a cushion stop 72 at which time a toggle 10 comprising links 67 and 68 is straightened to hold the carriage in upper case position until the depressed case-shift key is released. Upon release of the key a pawl at the rear side of the drive shaft engages the unit to move the actuator 70 15 upwardly and return the parts to original position with head of stud 66 against a stop 69. The case-shift mechanism herein briefly mentioned is fully described and claimed in my co-pending application filed Feb. 20, 1937, Serial No. 126,904.

An electric motor is positioned in a casing 73 at the rear of side wall 22. The motor is connected to continuously rotate the power-drive member 74 which, in the present preferred form 25 of the invention, is a toothed roller extending almost entirely across the machine and rotating in a counterclockwise direction, as viewed in Fig. 2 of the drawings.

Provision is also made for returning the carriage to commence a new line of writing by momentarily connecting the motor with a drum indicated at 74, which winds up a tape 75 connected to the carriage and line-spacing mechanism, and restores the carriage to starting position. The 35 connection is made through a friction clutch indicated at 76 which is rendered effective by pressure upon the carriage-return key at the keyboard (see Fig. 1). This carriage-return mechanism, together with means for line-spacing on 40 each return and for power-driven additional line-spacing, is clearly shown and described in my co-pending application filed Feb. 20, 1937, Serial No. 126,903, now Patent No. 2,103,921, issued Dec. 28, 1937.

In the present embodiment of the invention shown in the drawings the top plate 28 is adapted for the mounting of twenty-two type bars. Each of the type bars is adapted for actuation by the operation of either of two keys at the 50 keyboard. Except for minor differences due to the variations in angularity of mounting, all the type bars and their associated parts are identical and the following description of one type action will be sufficient for the purpose of the present case.

In Fig. 7 of the drawings an improved hanger 80 is shown. This hanger is made up of two or more thin metal pieces which may be held together by spaced rivets or suitably spot welded. 60 Thus a laminated hanger structure is produced which includes an arm 81 adapted to fit into a slot 82 cut in the arcuate bar 30 of the top plate 28. The laminated hanger 80 also comprises an arm 83 which is notched at 84 to fit it over 65 a rib 85 on the arcuate bar 32. A lower lip 86 of arm 83 fits in a radial slot through the bottom of bar 32 so that by the slots in the bottom of bar 32 and the slots in bar 30 the hangers 80 of a complete series are definitely located in substantially radial arrangement.

The hangers 80 are also provided with cushion stop and noise reducing features in the form of a slender bent-over finger 87 of the laminated hanger and in the form of a pile or bank 88 of 75

very thin metal strips arranged along the top of arm 81 and held in position thereon by straps 90 at opposite ends of the bank. The laminated finger 87 serves to cushion the blow and reduce the noise of impact of the lever which drives the type bar forward toward the printing point. The bank 88 of superposed thin spring metal strips cushions and reduces the noise of impact incident to the return of the type bar.

10 The hanger 80 is laminated in major part but beyond the arm 83 one of the sheet metal laminations is carried beyond the laminated structure providing an arm 91 which serves as a pivot support, as will hereinafter appear.

15 The type bars 34 suitably guided in comb slots 33, 35 and 36 are supported for pivotal movement on the hangers 80. Each type bar is connected to its hanger by two links 92 and 93. The link 92 is pivoted to the type bar 34 at 94 and the lower end 20 of link 92 is pivotally connected at 95 to an arm 96 which is adjustably fixed to the hanger 80. The link 93 has its upper end pivotally connected to the type bar 34 at 97 and its lower end connected to a rocker arm or link 98 which is pivoted 25 at 100 at the extreme end of arm 91 which was heretofore described as a continuation of one of the laminations of hanger 80. Thus it will be seen that link 92 has its lower connection substantially fixed except for possibility of slight 30 adjustment provided by eccentric adjusting device 101. Link 93, however, has its lower pivotal connection on rocker arm or link 98 and the axis of motion of link 93 may therefore be varied.

The type bar 34 is also connected to the hanger 35 80 through a toggle indicated generally at 102 comprising links 103 and 104. Link 103 comprises two uniformly shaped sheet metal pieces provided with a suitable spacer at 105 and is pivoted to the type bar 34 and link 40 92 at the pivot 94. The ends of the spaced members are brought together as indicated at 106 and 107 and at end 107 link 103 passes between spaced sides of link 104 and is pivoted thereto at 108. The other end of link 104 is pivoted to the hanger 45 80 at 110.

Link 104 is provided on both sides with arms 111 between which an end 112 of a hammer 113 is pivoted. A driving lever 114 is pivoted to hanger 80 at 115 and has a curved face 116 50 underlying the hanger 80 and the levers on opposite sides of the hanger as will hereinafter appear. Lever 114 has arms 117 extending upwardly on opposite sides of hanger 80 and their upper ends fork around hammer 113 and are pivotally secured thereto at 118. A bridge 120 joins the opposite sides of lever 114 and the lever is adapted, upon movement in a clockwise direction, as viewed in Fig. 2 of the drawings, to tension a spring 121 until bridge 120 abuts the finger stop 55 87 of the hanger.

Such movement tends to straighten the toggle 102 and advance the type bar 34 toward the platen 50. As will later appear, the driving lever 114 is not given its entire throw to stop position 60 under direct control of the power actuators of the machine, but instead the lever is moved part way under direct control of the power actuators and the final throw of the lever and consequent final advance of the type bar is effected by the 65 momentum accumulator or energy storing device 113 which ultimately straightens the toggle 102 and applies suitable printing pressure to whichever type is at the printing line. To vary this pressure the platen is adjusted fore and aft of 70 the machine by a hand wheel 122 on screw 53,

as clearly described in my copending application filed Feb. 20, 1937, Serial No. 126,902.

The type bar 34 is adapted to move toward the platen in two different curvilinear paths dependent upon the position of the pivotal axis X 5 of link 93 and this axis may be shifted from a fixed position shown in Figs. 2, 5 and 6 of the drawings to a fixed position as shown in Figs. 3 and 4. The movement of the axis X from one position to the other and the fixing of the axis in 10 the different positions is effected by a system of levers and toggle links which will be later described.

The power drive mechanism comprises primarily the toothed or fluted roller 71 which is 15 continuously rotated in a counter-clockwise direction, as viewed in Fig. 2, from the electric motor positioned in the casing 73. The backbone 25 has a flange 123 extending downwardly at a right angle to its body. It also has an upwardly 20 extending flange 109 and a rearwardly extending flange 119. By a circular gang cutter a series of slots 124 is cut in the rear of the backbone and these slots are cut deep enough that the peripheries of the cutters pass through the flanges 109 25 and 119 and through the shoulder formed by the body and flange 123 of the backbone. Thus at 125 (Fig. 2) the slots extend entirely through the backbone for a purpose which will later appear. In each of the slots 124 an actuator 126 is arranged. These actuators are substantially uniform in character having an easy sliding movement in the slots and they are located in transverse alignment by a pivot pin or rod 127 which passes through the flange 119 and through a vertical slot 128 in each of the actuators. Each of the actuators carries a pawl 130 pivoted thereon at 131 and having teeth 132 to engage with the teeth of drive shaft 71. A forward edge 133 of each actuator bears against the rear face of 30 flange 123 of backbone 25 and is normally held thereagainst by a spring 134 the lower end of which engages a lower arm 135 of the actuator and the upper end of which is connected to an anchor plate 136 secured to the under side of 35 flange 123. Spring 134 causes the actuator to pivot around pin 127 and hold pawl 130 normally out of engagement with the drive shaft.

A standard 4-band keyboard is indicated at 40 137. Each character key on the keyboard is 50 associated with a key lever 138 the end 140 of which extends into one of the slots 124 in the flange 109 of the backbone and is pivotally connected therewith by a pivot pin 141. Each key lever also has an arm 142 which carries a dog 143 pivoted at 144 and normally held in the position indicated in Fig. 2 by a spring 145. Each dog 143 passes through the opening provided at 125 by the gang cutting of slots 124 and, therefore, for each actuator arranged within a slot 124 there is a dog 143 in the same slot in position to move the actuator upon depression of the corresponding key lever 138. Such lever movement engages pawl 130 with drive roller 71 which causes an approximately 30° rotation of pawl 130 against a suitable stop and a simultaneous downward movement of the actuator. The engagement of the first tooth of the pawl leads the second tooth into actuating engagement with the next tooth of the drive roller. A lug 146 near the lower end of the actuator passes between the balls of a crowder lock 147 and simultaneously the actuator picks up a universal bar 148 and rocks it for the purpose of effecting escapement and ribbon vibration operations. As

the actuator proceeds downwardly in engagement with the drive roller a cam edge 150 of the actuator engages an adjustable throw-off screw 151 which insures disengagement of pawl 130 with the driving shaft and causes it to be returned to the control of spring 134 which eventually draws the actuator back against the rear face of the backbone.

In addition to the actuators which are placed 10 in engagement with the drive shaft by operation of the character keys, there are similar actuators in the same row under control of the space bar (indicated at 152 in Figs. 1 and 2), the carriage shift key, tabulator bar 149, and various 15 other keys controlling the operation of the typewriter. These actuators are all carried by the backbone which also guides and pivots the key levers and also guides the actuating dogs, the function of which is to engage the actuators with 20 the driving shaft.

A bar 153 of sound deadening material such as 25 rubber or leather extends transversely on the machine in a metal support 154 and is adapted to receive the impact of arms 135 of the actuators as they are thrown off by screws 151 and returned to normal position by their return springs 134. The face of bar 153 is set at a slight angle so that as the actuator returns upwardly to its 30 original position the end of arm 135 may slide along this face until eventually the actuator is deposited against the backbone. All of the key levers have return springs 155 connected to an 35 adjustable anchor plate 156. The springs normally hold the key lever against an upper stop 40 157 of cushioning material and the key levers have a uniform movement of depression to a lower stop 158, as clearly described and claimed in my copending application filed Feb. 20, 1937, Serial No. 126,905.

According to the present invention, each type 45 bar is controlled by two different keys and consequently by two actuators. Preferably, therefore, the actuators 126 are arranged in successive pairs across the machine. From the upper ends of 50 the actuators of one pair links 160 and 161 extend respectively to opposite sides of each hanger 80. Link 160 is pivotally connected at 162 to a rock lever 163 which is pivoted on the hanger 80 at 164. This lever has a circular hole 165 55 within which extends a stop pin 166 extending laterally from the hanger 80. The hole 165 and pin 166 determine the extremes of movement of lever 163. Thus, viewing the construction in Fig. 2 of the drawings, as an actuator 126 is 60 engaged with the power drive shaft and moved downwardly, link 160 pulls down the forward end of lever 163 until the lower edge of hole 165 abuts the stop pin 166. The rear end of the lever is thus thrown upwardly to a stop position, 65 which is clearly shown in Fig. 4. This end of the lever is pivotally connected to one end of a link 167, the other end of which is pivotally connected at 168 intermediate the pivoted ends of a link 170. The lower pivoted end 171 of this 70 link is connected to rocker 98 which, as heretofore described, is pivoted at 100 on the end of the hanger 80 and the other end of which carries the variable pivot X of link 93. The upper end of link 170 is connected by a short link 172 with a bracket arm 173 fixed to the hanger 80. Thus a downward pull on point 162 of the lever 163 straightens a toggle from stop 166 through the lever 163 to a toggle point T, thence through link 167 to pivot point 168 (see Fig. 3). This definitely fixes the position of link 170, rocker

98 and the pivotal axis X. While this toggle is straightened the point X will not vary.

As lever 163 is being pulled down to its stop position by its actuator and link 160, a forward rocker end 174 of the lever engages with curved face 116 of the drive lever 114 and rocks the drive lever around its pivot 115 to commence the straightening of toggle 102. Lever 163 arrives at its stop and toggle-locked position before the drive lever 114 has completed its full movement. It is at this point that the energy storing device 113 picks up the movement of the type bar and carries it forward until bridge 120 of the drive lever strikes against stop 87 at which time the toggle 102 is straightened and the lower case 15 type of the upper head of type bar 34 is brought into printing engagement with the paper on the platen (Fig. 3).

Lever 163 has its rocker end supplemented by a guard 175 pivoted to the lever at 176 and 20 pressed by spring 177 to normally hold a stop lip 178 on the guard against the rocker end of the lever. The drive lever 114 has a laterally extending pin 180 which rides along the upper edge of guard 175 when the hammer 113 is in control 25 of the movement of the type bar toward the platen. Spring 121 returns the drive lever 114 in the opposite direction and during the first part of this returning movement pin 180 rides along the top edge of guard 175 in the opposite direction. Therefore, the toggle comprising lever 163 and link 167 may not be broken from the time that the hammer 113 has started to pick up the movement of the type bar to the time that this hammer has returned under the influence of the 30 spring to a point in the operation in which the type bar has substantially moved away from the printing point. The spring 121 continues to return the drive lever until the hammer 113 is 35 rocked back onto the bank of thin strips which 40 constitute its cushion stop, as heretofore described.

While the pin on the drive lever is riding along the guide 175 in one direction or the other, the corresponding actuator 126 is, of course, held 45 against return to its upper normal position although it has been rejected from its engagement with the driving shaft by the engagement of throw-off pin 151 with cam edge 150 of the actuator. As soon, however, as the pin 180 rides over 50 the end of guard 175 the actuator is returned upwardly by its spring 134 and carries with it the connector 160 thus moving upwardly the rocker end of lever 163 breaking the toggle 163-167 and swinging the axis of movement X of link 93 55 substantially toward the position shown in Figs. 5 and 6 of the drawings.

An adjacent actuator 126 controlled by another character key at the keyboard has its upper end connected by connector 161 to a lever 181 60 pivoted at 182 on the opposite side of hanger 80. This lever has a rocker end 183 adapted to engage the curved face 116 of the drive lever 114 to move the drive lever in the same manner as moved by lever 163 to institute the straightening 65 of toggle 102 and thrust the type bar 34 toward the platen. However, lever 181 when moved by its actuator first straightens the toggle comprising the links 170 and 172 against a guard 179 and moves the rocker 98 into a firmly held position indicated in Figs. 5 and 6 of the drawings. This is accomplished in the following manner. It is possible that the return of the actuator for lever 163 may have been of sufficient energy to throw the lever over until the upper side of hole 70 75

165 contacted with the pin 166 in which case the toggle 170—172 would be straightened and the parts would appear in the position shown in Fig. 5 of the drawings even though connector 161 had not been pulled down by its actuator. When the actuator is pulled down the lever 181, being notched at 185 around a stop pin 186 which extends from the side of the hanger, is swung from the position shown in Fig. 5 until it is stopped by engagement with pin 186, as shown in Fig. 6 of the drawings. This lever is connected by curved link 187 which lies beneath the hanger 80 with an arm 188 of a bell crank lever 190 pivoted at 191 on the hanger 80. The other arm 192 of the bell crank lever lies on the side of the hanger opposite lever 181 and its end is adapted to engage with lever 163 just above the hole 165. Swinging of lever 181 to its stop position as shown in Fig. 6 of the drawings operates the bell crank lever 190 to throw lever 163 downwardly until the upper side of the hole 165 engages the stop pin 166. Thus the straightening of toggle 170—172 is insured and the rocker 98 is definitely and firmly positioned as shown in Fig. 6 of the drawings, which changes the axis of motion of one of the type bar supporting links in consequence of which the type bar is moved forwardly by the drive lever in a different path to impress the lower case character of the lower head of the type bar against the paper on the platen. The lever 181 is supplemented by a guard 189 similar to the one on lever 163 and the drive lever has on its opposite arm 117 a pin 192 which drives in the same manner over the guard 189 preventing any disturbance in the position of the pivotal point of link 93 while the hammer 113 is in control of the advance or retraction of the type bar.

For upper case printing by either the upper or lower heads of the type bars the carriage is shifted to an upper toggle-locked position by actuators similar to those described in connection with the character keys and as more particularly described and claimed in my copending application filed Feb. 20, 1937, Serial No. 126,904.

The carriage is provided with a letter feed escapement indicated at 193 operated from the universal bar 148, which is in turn power operated as any character lever or the space bar is depressed. This escapement includes a shaft 194 splined at its lower end to accommodate the carriage to escapement in either upper or lower case position, and the upper end of this shaft is provided with a pinion 195 meshing with a rack 196 on the carriage. The escapement dogs are thrown out of engagement when tabulating, as clearly shown and described in my copending application filed April 1, 1937, Serial No. 134,324.

What is claimed is:

1. In a typewriter, a frame, a plurality of type actions segmentally arranged relatively to said frame, each type action comprising a hanger secured to the frame, a type bar, a toggle between the type bar and the hanger, a supporting link

for the type bar having one end pivotally connected to the bar and its other end pivoted in fixed relation to the hanger, a rocker member pivoted on the hanger, a second type bar supporting link having one end connected to the type bar and its other end connected to the rocker member on one side of its pivot, a toggle link extending from said rocker member at the other side of its pivot, another toggle link having one end pivotally connected to the first said toggle link and its other end held fixed for pivotal movement relatively to the hanger, a lever pivotally mounted on one side of the hanger, a toggle link pivoted to the first said toggle link having its end connected pivotally with an end of said lever, means for connecting the other end of said lever to an actuator, means for limiting the range of pivotal movement of said lever, another lever pivotally mounted for movement in a limited range at the other side of the hanger and having means for connecting one end with an actuator, a finger connected for movement by the last said lever to insure straightening of a toggle comprising the first and second said toggle links, and a driving lever operable by either of the aforesaid levers to actuate the toggle between the type bar and the hanger.

2. In a typewriter, a frame, a plurality of type actions segmentally arranged relatively to said frame, each type action comprising a hanger secured to the frame, a type bar, a toggle between the type bar and the hanger, a supporting link for the type bar having one end pivotally connected to the bar and its other end pivoted in fixed relation to the hanger, a rocker member pivoted on the hanger, a second type-bar-supporting link having one end connected to the type bar and its other end connected to the rocker member on one side of its pivot, a toggle link extending from said rocker member at the other side of its pivot, another toggle link having one end pivotally connected to the first said toggle link and its other end held fixed for pivotal movement relatively to the hanger, a lever pivotally mounted on one side of the hanger, a toggle link pivoted to the first said toggle link having its end connected pivotally with an end of said lever, means for connecting the other end of said lever to an actuator, means for limiting the range of pivotal movement of said lever, another lever pivotally mounted for movement in a limited range at the other side of the hanger and having means for connecting one end with an actuator, a finger connected for movement by the last said lever to insure straightening of a toggle comprising the first and second said toggle links, a driving lever operable by either of the aforesaid levers to actuate the toggle between the type bar and the hanger, and an energy storing device initially movable by the drive lever and subsequently movable by its accumulated energy to straighten the toggle between the type bar and the hanger.

RUSSELL G. THOMPSON.
